S-(N-ACYL-N-ALKYL OR
PHENYL-AMIDOCARBONYL)-METHYL-THIO-
PHOSPHORIC AND -PHOSPHONIC ACID ESTERS

The present invention relates to and has for its objects the provision of particular new S-(N-acyl-N-alkyl or phenylamidocarbonyl)-methyl-thiophosphoric and -phosphonic acid esters, i.e. S-(N-alkanoyl- or -benzoyl-N-alkyl- or -phenyl-amidocarbonyl)-methyl-mono- or di-thiophosphoric acid alkyl esters or the alkane-phosphonic acid ester counterparts thereof, which are optionally halogen-substituted on the benzene ring, which possess insecticidal and acaridical properties, active compositions in the form of mixtures of such compounds with solid and liquid dispersible carrier vehicles and methods for producing such compounds and for using such compounds in a new way especially for combating pests, e.g. insects and acarids, with other and further objects becoming apparent from a study of the within specification and accompanying examples.

It is known from German Published DAS Nos. 1,148,806 and 1,143,052, and British Patent Specification 867,780 that the reaction products of O,O-dialkyl-thiophosphoric acid salts with certain halogenoacetic acid N-acylamides are distinguished by insecticidal and acaridical activity.

The present invention provides, as new compounds, the S-(N-acylamidocarbonyl)-methyl-mono- or -di-thio-phosphoric or -phosphonic acid esters of the general formula

in which

R is alkyl of 1 to 6 carbon atoms,
R' is alkyl or alkoxy of 1 to 6 carbon atoms,
R'' is alkyl of 1 to 6 carbon atoms or phenyl,
Acyl is (C₁-C₆-alkyl) carbonyl or phenylcarbonyl, and
X is oxygen or sulfur.

Preferably, R is straight-chain or branched lower alkyl with 1 to 4 carbon atoms (namely methyl, ethyl, iso- or n-propyl, or n-, iso-, sec.- or tert.-butyl); R' is straight-chain or branched lower alkyl as R or lower alkoxy with, in either case, 1 to 4 carbon atoms (such as methoxy, ethoxy, iso- or n-propoxy or n-, iso, sec.- or tert.-butoxy); R'' is straight-chain or branched lower alkyl with 1 to 4 carbon atoms or phenyl; and Acyl is acetyl, propionyl, butyryl, isobutyryl or benzoyl.

Surprisingly, the S-(N-acyl-amidocarbonyl)-methyl-thiophosphoric acid esters and thiophosphonic acid esters of the formula (I) possess a substantially better insecticidal and acaridical action than the prior art S-(N-acyl-amidocarbonyl)-methyl-thiophosphoric acid esters which are not only the nearest comparable compounds with regard to structure and type of activity but also the best-known commercially available products of this class of substance, and from which the compounds according to the invention differ in respect of the nature of the acyl radical. The new compounds thus represent an enrichment of the art.

The present invention also provides a process for the preparation of an S-(N-acylamidocarbonyl)-methyl-

mono- or -di-thiophosphoric acid ester or thiophosphonic acid ester of the formula (I) in which an O,O-dialkyl-mono- or -di-thiophosphoric acid salt or thiophosphonic acid salt of the general formula

10 is reacted with a halogenoacetic acid N-acyl amide of the general formula

in which formulas

20 R, R', R'', Acyl and X have the above-mentioned meanings,

Hal is a halogen atom, preferably bromine or chlorine, and

25 M is an alkali metal equivalent, alkaline earth metal equivalent or optionally alkyl-substituted ammonium equivalent.

If the sodium salt of O,O-dimethyldithiophosphoric acid and chloroacetic acid N-acetyl-N-methylamide are used as starting materials, the course of the reaction can be represented by the following equation:

45 The following may be mentioned as examples of the O,O-dialkyl-mono- or -di-thiophosphoric acid salts or thiophosphonic acid salts (II) which can be used: the alkali metal salts, alkaline earth metal salts and optionally alkylsubstituted ammonium salts of O-methyl-O-isopropyl-, O-ethyl-O-isopropyl-, O,O-di-n-propyl,

50 O,O-di-isopropyl- and O,O-di-sec.-butyl-mono- and -di-thiophosphoric acids and the corresponding salts of O-methyl, O-ethyl- and O-isopropyl-methane-mono- and -di-thiophosphonic acids and isopropane-mono- and -di-thiophosphonic acids.

Examples of suitable halogenoacetic acid N-acylamides (III) are: chloroacetic acid or bromoacetic acid N-acetyl-N-ethyl-, N-acetyl-N-n-butyl-, N-acetyl-N-sec.-butyl-, N-propionyl-N-methyl-, N-propionyl-N-ethyl-, N-propionyl-N-isopropyl-, N-propionyl-N-sec.-butyl-, N-isobutyryl-N-ethyl-, N-isobutyryl-N-isopropyl-, N-isobutyryl-N-sec.-butyl-, N-benzoyl-N-ethyl-, N-benzoyl-N-isopropyl-, N-benzoyl-N-sec.-butyl-, N-isobutyryl-N-phenyl- and N-benzoyl-N-phenyl-amides.

65 The (di)thiophosphoric and (di)thiophosphonic acid salts (II) and the halogenoacetic acid derivatives (III) are known and can be prepared according to customary methods.

The preparative process for the new compounds (I) is preferably carried out with conjoint use of a suitable solvent or diluent. As such, practically all inert organic solvents can be used, especially aliphatic and aromatic, optionally chlorinated, hydrocarbons such as benzene, toluene, xylenes, benzine, methylene chloride, chloroform, carbon tetrachloride and chlorobenzene; ethers, for example diethyl ether, dibutyl ether and dioxane; ketones, for example acetone, methyl ethyl ketone, methyl isopropyl ketone and methyl isobutyl ketone; nitriles, such as acetonitrile and propionitrile; and alcohols, for example methanol, ethanol and isopropanol. In certain cases, water is also suitable as a solvent.

The reaction temperature can be varied within a fairly wide range. In general, the reaction is carried out at from 0° to 120°C, preferably at from 15° to 60°C.

The reaction is in general carried out under normal pressure.

For carrying out the process, the starting materials are in most cases employed in equimolar amounts. An excess of one or other reactant produces no substantial advantages. The reaction is preferably carried out in the presence of one of the above-mentioned solvents, at the indicated temperatures, and the reaction mixture is worked up in the usual manner after stirring for several hours.

The compounds according to the invention are in most cases obtained in the form of colorless to slightly colored viscous, water-soluble oils or crystalline products which in general cannot be distilled without decomposition but can be freed of the last volatile constituents by so-called "slight distillation," that is to say prolonged heating to moderately elevated temperatures under reduced pressure, and can be purified in this way. They are characterized, in particular, by the refractive index and, in the case of solid compounds, by the melting point.

As has already been mentioned, the new S-(N-acylamidocarbonyl)-methylthiophosphoric acid esters and thiophosphonic acid esters are distinguished by an excellent insecticidal, acaricidal and soil-insecticidal activity against plant pests, pests of stored products and pests harmful to health. They possess a good action against both sucking and biting insects and against mites (*Acarina*). At the same time, they show only a slight phytotoxicity.

For these reasons, the compounds according to the invention may be successfully employed as pesticides in plant protection and in the hygiene field.

To the sucking insects there belong, in the main, aphids (*Aphidae*) such as the green peach aphid (*Myzus persicae*), the bean aphid (*Doralis fabae*), the bird cherry aphid (*Rhopalosiphum padi*), the pea aphid (*Macrosiphum pisi*) and the potato aphid (*Macrosiphum solanifoli*), the current gall aphid (*Cryptomyzus korschelti*), the rosy apple aphid (*Sappaphis malii*), the mealy plum aphid (*Hyalopterus arundinis*) and the cherry black-fly (*Myzus cerasi*); in addition, scales and mealybugs (*Coccina*), for example the oleander scale (*Aspidiotus hederae*) and the soft scale (*Lecanium hesperidum*) as well as the grape mealybug (*Pseudococcus maritimus*); thrips (*Thysanoptera*), such as *Hercinothrips femoralis*, and bugs, for example the beet bug (*Piesma quadrata*), the red cotton bug (*Dysdercus intermedius*), the bed bug (*Cimex lectularius*), the assassin bug (*Rhodnius prolixus*) and Chagas' bug (*Triatoma infestans*) and, further, cicadas, such as *Euscelis bilobatus* and *Nephrotettix bipunctatus*.

In the case of the biting insects, above all there should be mentioned butterfly caterpillars (*Lepidoptera*) such as the diamond-back moth (*Plutella maculipennis*), the gypsy moth (*Lymantria dispar*), the brown-tail moth (*Euproctis chrysorrhoea*) and tent caterpillar (*Malacosoma neustria*); further, the cabbage moth (*Mamestra brassicae*) and the cutworm (*Agrotis segetum*), the large white butterfly (*Pieris brassicae*), the small winter moth (*Cheimatobia brumata*), the green oak tortrix moth (*Tortrix viridana*), the fall armyworm (*Laphygma frugiperda*) and cotton worm (*Prodenia litura*), the ermine moth (*Hyponomeuta padella*), the Mediterranean flour moth (*Ephestia kuhniella*) and greater wax moth (*Galleria mellonella*).

Also to be classed with the biting insects are beetles (*Coleoptera*), for example the granary weevil (*Sitophilus granarius* = *Calandra granaria*), the Colorado beetle (*Leptinotarsa decemlineata*), the dock beetle (*Gastrophysa viridula*), the mustard beetle (*Phaedon cochleariae*), the blossom beetle (*Meligethes aeneus*), the raspberry beetle (*Byturus tomentosus*), the bean weevil (*Bruchidius* = *Acanthoscelides obtectus*), the leather beetle (*Dermestes frischii*), the khapra beetle (*Trogoderma granarium*), the flour beetle (*Tribolium castaneum*), the northern corn billbug (*Calandra* or *Sitophilus zeamais*), the drugstore beetle (*Stegobium paniceum*), the yellow mealworm (*Tenebrio molitor*) and the sawtoothed grain beetle (*Oryzaephilus surinamensis*), and also species living in the soil, for example

wireworms (*Agriotes* spec.) and larvae of the cockchafer (*Melolontha melolontha*); cockroaches, such as the German cockroach (*Blattella germanica*), American cockroach (*Periplaneta americana*), Madeira cockroach (*Leucophaea* or *Rhyparobia maderae*), oriental cockroach (*Blatta orientalis*), the giant cockroach (*Blaberus giganteus*) and the black giant cockroach (*Blaberus fuscus*) as well as *Henschoutedenia flexivitta*; further, *Orthoptera*, for example the house cricket (*Acheta domesticus*); termites such as the eastern subterranean termite (*Reticulitermes flavipes*) and *Hymenoptera* such as ants, for example the garden ant (*Lasius niger*).

The *Diptera* comprise essentially the flies, such as the vinegar fly (*Drosophila melanogaster*), the Mediterranean fruit fly (*Ceratitis capitata*), the house fly (*Musca domestica*), the little house fly (*Fannia canicularis*), the black blow fly (*Phormia regina*) and bluebottle fly (*Calliphora erythrocephala*) as well as the stable fly (*Stomoxys calcitrans*); further, gnats, for examples mosquitoes such as the yellow fever mosquito (*Aedes aegypti*), the northern house mosquito (*Culex pipiens*) and the malaria mosquito (*Anopheles stephensi*).

With the mites (*Acarina*) there are classed, in particular, the spider mites (*Tetranychidae*) such as the two-spotted spider mite (*Tetranychus urticae*) and the European red mite (*Paratetranychus pilosus* = *Panonychus ulmi*), gall mites, for example the blackcurrent gall mite (*Eriophyes ribis*) and tarsonemids, for example the broad mite (*Hemitarsonemus latus*) and the cyclamen mite (*Tarsonemus pallidus*); finally, ticks, such as the relapsing fever tick (*Ornithodoros moubata*).

When applied against pests harmful to health and pests of stored products, particularly flies and mosquitoes, the present compounds are also distinguished by an outstanding residual activity on wood and clay, as well as a good stability to alkali on limed substrates.

The active compounds according to the instant invention can be utilized, if desired, in the form of the

usual formulations or compositions with conventional inert (i.e. plant compatible or herbicidally inert) pesticide diluents or extenders, i.e. diluents, carriers or extenders of the type usable in conventional pesticide formulations or compositions, e.g. conventional pesticide dispersible carrier vehicles such as gases, solutions, emulsions, suspensions, emulsifiable concentrates, spray powders, pastes, soluble powders, dusting agents, granules, etc. These are prepared in known manner, for instance by extending the active compounds with conventional pesticide dispersible liquid diluent carriers and/or dispersible solid carriers optionally with the use of carrier vehicle assistants, e.g. conventional pesticide surface-active agents, including emulsifying agents and/or dispersing agents, whereby, for example, in the case where water is used as diluent, organic solvents may be added as auxiliary solvents. The following may be chiefly considered for use as conventional carrier vehicles for this purpose: aerosol propellants which are gaseous at normal temperatures and pressures, such as freon; inert dispersible liquid diluent carriers, including inert organic solvents, such as aromatic hydrocarbons (e.g. benzene, toluene, xylene, alkyl naphthalenes, etc.), halogenated, especially chlorinated, aromatic hydrocarbons (e.g. chlorobenzenes, etc.), cycloalkanes (e.g. cyclohexane, etc.), paraffins (e.g. petroleum or mineral oil fractions), chlorinated aliphatic hydrocarbons (e.g. methylene chloride, chloroethylenes, etc.), alcohols (e.g. methanol, ethanol, propanol, butanol, glycol, etc.) as well as ethers and esters thereof (e.g. glycol monomethyl ether, etc.), amines (e.g. ethanolamine, etc.), amides (e.g. dimethyl formamide, etc.), sulfoxides (e.g. dimethyl sulfoxide, etc.), acetonitrile, ketones (e.g. acetone, methyl ethyl ketone, methyl isobutyl ketone, cyclohexanone, etc.), and/or water; as well as inert dispersible finely divided solid carriers, such as ground natural minerals (e.g. kaolins, clays, alumina, silica, chalk, i.e. calcium carbonate, talc, attapulgite, montmorillonite, kieselguhr, etc.) and ground synthetic minerals (e.g. highly dispersed silicic acid, silicates, e.g. alkali silicates, etc.); whereas the following may be chiefly considered for use as conventional carrier vehicle assistants, e.g. surface-active agents, for this purpose: emulsifying agents, such as non-ionic and/or anionic emulsifying agents (e.g. polyethylene oxide esters of fatty acids, polyethylene oxide ethers of fatty alcohols, alkyl sulfates, alkyl sulfonates, aryl sulfonates, albumin hydrolyzates, etc., and especially alkyl arylpolyglycol ethers, magnesium stearate, sodium oleate, etc.); and/or dispersing agents, such as lignin, sulfite waste liquors, methyl cellulose, etc.

Such active compounds may be employed alone or in the form of mixtures with one another and/or with such solid and/or liquid dispersible carrier vehicles and/or with other known compatible active agents, especially plant protection agents, such as other insecticides, and acaricides, or rodenticides, fungicides, bactericides, nematocides, herbicides, fertilizers, growth-regulating agents, etc., if desired, or in the form of particular dosage preparations for specific application made therefrom, such as solutions, emulsions, suspensions, powders, pastes, and granules which are thus ready for use.

As concerns commercially marketed preparations, these generally contemplate carrier composition mixtures in which the active compound is present in an amount substantially between about 0.1-95 percent by

weight, and preferably 0.5-90 percent by weight, of the mixture, whereas carrier composition mixtures suitable for direct application or field application generally contemplate those in which the active compound is present in an amount substantially between about 0.0001-10 percent, preferably 0.01-1 percent, by weight of the mixture. Thus, the present invention contemplates over-all compositions which comprises mixtures of a conventional dispersible carrier vehicle such as (1) a dispersible inert finely divided carrier solid, and/or (2) a dispersible carrier liquid such as an inert organic solvent and/or water preferably including a surface-active effective amount of a carrier vehicle assistant, e.g. a surface-active agent, such as an emulsifying agent and/or a dispersing agent, and an amount of the active compound which is effective for the purpose in question and which is generally between about 0.0001-95 percent, and preferably 0.01-95 percent, by weight of the mixture.

The active compounds can also be used in accordance with the well known ultra-low-volume process with good success, i.e. by applying such compound if normally a liquid, or by applying a liquid composition containing the same, via very effective atomizing equipment, in finely divided form, e.g. average particle diameter of from 50-100 microns, or even less, i.e. mist form, for example by airplane crop spraying techniques. Only up to at most about a few liters/hectare are needed, and often amounts only up to about 15 to 1000 g/hectare, preferably 40 to 600 g/hectare, are sufficient. In this process it is possible to use highly concentrated liquid compositions with said liquid carrier vehicles containing from about 20 to about 95 percent by weight of the active compound or even the 100 percent active substance alone, e.g. about 20-100 percent by weight of the active compound.

Furthermore, the present invention contemplates methods of selectively killing, combating or controlling pests, e.g. insects and acarids, which comprises applying to at least one of correspondingly (a) such insects, (b) such acarids, and (c) the corresponding habitat thereof, i.e. the locus to be protected, a correspondingly combative or toxic amount, i.e. and insecticidally or acaricidally effective amount, of the particular active compound of the invention alone or together with a carrier vehicle as noted above. The instant formulations or compositions are applied in the usual manner, for instance by spraying, atomizing, vaporizing, scattering, dusting, watering, squirting, sprinkling, pouring, fumigating, dressing, encrusting, and the like.

It will be realized, of course, that the concentration of the particular active compound utilized in admixture with the carrier vehicle will depend upon the intended application. Therefore, in special cases it is possible to go above or below the aforementioned concentration ranges.

The synthesis, unexpected superiority and outstanding activity of the particular new compounds of the present invention are illustrated, without limitation, by the following examples:

EXAMPLE 1

Plutella test

Solvent: 3 parts by weight of acetone

Emulsifier: 1 part by weight of alkylaryl polyglycol ether

To produce a suitable preparation of active compound, 1 part by weight of the active compound was

mixed with the stated amount of solvent containing the stated amount of emulsifier and the concentrate was diluted with water to the desired concentration.

Cabbage leaves (*Brassica oleracea*) were sprayed with the preparation of the active compound until dew moist and were then infested with caterpillars of the diamond-back moth (*Plutella maculipennis*).

After the specified periods of time, the degree of destruction was determined as a percentage: 100% means that all the caterpillars were killed whereas 0% means that none of the caterpillars were killed.

The active compounds, the concentrations of the active compounds, the evaluation times and the results can be seen from the following Table 1:

Table 1

(Plutella test)			
Active compound	Active compound concentration in %	Degree of destruction in % after 3 days	
<chem>SC(=S)P(=O)(OCC)SC-C(=O)N(C)C</chem> (known) (A)	0.1 0.01	100 0	
<chem>SC(=S)P(=O)(OCC)SC-C(=O)N(C)C</chem> (known) (B)	0.1 0.01	70 0	
<chem>CC(=O)N(C)C(=O)CSC(=S)P(=O)(OCC)SC</chem> (10)	0.1 0.01	100 100	
<chem>CC(=O)N(C)C(=O)CSC(=S)P(=O)(OCC)SC</chem> (12)	0.1 0.01	100 100	

EXAMPLE 2

Myzus test (contact action)
Solvent: 3 parts by weight of acetone

percent means that none of the aphids were killed.
The active compounds, the concentrations of the active compounds, the evaluation times and the results can be seen from the following Table 2:

Table 2

(Myzus test)			
Active compound	Active compound concentration in %	Degree of destruction in % after 1 day

EXAMPLE 3

Rhopalosiphum test (systemic action)

Solvent: 3 parts by weight of acetone

Emulsifier: 1 part by weight of alkylaryl polyglycol ether

To produce a suitable preparation of active compound, 1 part by weight of the active compound was mixed with the stated amount of solvent containing the stated amount of emulsifier and the concentrate was diluted with water to the desired concentration.

Oat plants (*Avena sativa*) which had been strongly infested with the bird cherry aphid (*Rhopalosiphum*

padi) were watered with the preparation of the active compound so that the preparation penetrated into the soil without wetting the leaves of the oat plants. The active compound was taken up by the oat plants from the soil and thus reached the infested leaves.

After the specified periods of time, the degree of destruction was determined as a percentage: 100 percent means that all the aphids were killed whereas 0 percent means that none of the aphids were killed.

The active compounds, the concentrations of the active compounds, the evaluation times and the results can be seen from the following Table 3:

Table 3

(Rhopalosiphum test/systemic action)

Active compound	Active compound concentration in %	Degree of destruction in % after 4 days

EXAMPLE 4

Tetranychus test (resistant)

Solvent: 3 parts by weight of acetone

Emulsifier: 1 part by weight of alkylaryl polyglycol ether

To produce a suitable preparation of active compound, 1 part by weight of the active compound was mixed with the stated amount of solvent containing the stated amount of emulsifier and the concentrate was diluted with water to the desired concentration.

Bean plants (*Phaseolus vulgaris*), which had a height of approximately 10-30 cm, were sprayed with preparation of the active compound until dripping wet.

These bean plants were heavily infested with the two-spotted spider mite (*Tetranychus urticae*) in all stages of development.

After the specified periods of time, the effectiveness of the preparation of active compound was determined by counting the dead mites. The degree of destruction thus obtained is expressed as a percentage: 100 percent means that all the spider mites were killed whereas 0 percent means that none of the spider mites were killed.

The active compounds, the concentrations of the active compounds, the evaluation times and the results can be seen from the following Table 4:

Table 4

(Tetranychus test/resistant)

Active compound	Active compound concentration in %	Degree of destruction in % after 2 days
	0.1 0.01	40 0

Table 4-continued

(Tetranychus test/resistant)

Active compound	Active compound concentration in %	Degree of destruction in % after 2 days
	0.1	100
	0.1	98
	0.1	98
	0.1 0.01	100 95
	0.1	100
	0.1 0.01	100 85
	0.1	98
	0.1	100
	0.1 0.01	100 90
	0.1	98
	0.1 0.01	100 70

The process of the present invention is illustrated in the following preparative Example.

EXAMPLE 5

139.4 g (0.93 mole) of chloroacetic acid N-acetyl-N-methylamide were added dropwise, at room temperature, to a solution of 168.0 g (0.93 mole) of the sodium salt of O,O-dimethyl-dithiophosphoric acid in 600 ml of acetonitrile. The reaction was weakly exothermic. Stirring the mixture was continued overnight at 40° to 50°C. The inorganic salts which had separated out were filtered off, the solvent was removed and the residue was taken up in dichloromethane. The solution was twice washed with water and the organic phase was dried over sodium sulfate and filtered. The filtrate was concentrated and S-(N-acetyl-N-methylamidocarbonyl)-methyl-dithiophosphoric acid O,O-dimethyl ester was obtained as a brown oil which solidified after a short time. The crystalline product had a melting point of 48° to 49°C. The yield was 210.0 g (64.8% of theory).

The following compounds were obtained by methods analogous to that above:

-continued

Formula	Refractive index or melting point
	$n_D^{20} = 1.5325$
	$n_D^{20} = 1.5198$
	$n_D^{20} = 1.5332$
	$n_D^{20} = 1.4889$
	$n_D^{20} = 1.4855$
	$n_D^{20} = 1.5313$
	$n_D^{20} = 1.5725$

Other compounds which can be similarly prepared include:

(50) S-(N-propionyl-N-n-butyl-amidocarbonyl)-methyl-dithiophosphoric acid O-propyl-O-n-butyl ester,
 S-(N-benzoyl-N-ethyl-amidocarbonyl)-methyl-isopropanethiolphosphonic acid O-isobutyl ester,
 S-(N-valeryl-N-isopropyl-amidocarbonyl)-methyl-methanethiolphosphonic acid O-t-butyl ester,
 (55) S-(N-benzoyl-N-phenyl-amidocarbonyl)-methyl-butanedithiophosphoric acid O-isopropyl ester, and the like.

(60) It will be appreciated that the instant specification and examples are set forth by way of illustration and not limitation, and that various modifications and changes may be made without departing from the spirit and scope of the present invention.

(65) What is claimed is:

1. The compound S-(N-acetyl-N-methyl-amidocarbonyl)-methyl-dithiophosphoric acid O,O-dimethyl ester of the formula

17

2. The compound S-(N-acetyl-N-methyl-amidocarbonyl)-methyl-dithiophosphoric acid O,O-diethyl ester of the formula

5

3. The compound S-(N-acetyl-N-methyl-amidocarbonyl)-methylthiolphosphoric acid O,O-diethyl ester of the formula

10 4. The compound S-(N-benzoyl-N-methyl-amidocarbonyl)-methyl-ethanedithiophosphonic acid O-ethyl ester of the formula
